UNITED STATES PATENT OFFICE.

JOHN JOSEPH COOPER, OF LONDON, ENGLAND, ASSIGNOR TO UNDERWOOD TYPEWRITER COMPANY, OF NEW YORK, N. Y., A CORPORATION OF NEW JERSEY.

TYPE-WRITING MACHINE.

1,122,865.

Specification of Letters Patent. Patented Dec. 29, 1914.

Application filed April 16, 1910. Serial No. 555,800.

To all whom it may concern:

Be it known that I, JOHN JOSEPH COOPER, a subject of the King of Great Britain, and resident of 120 Queen Victoria street, London, England, type-writer mechanic, have invented certain new and useful Improvements in Type-Writing Machines, of which the following is a specification.

This invention relates to means for controlling the revolution of the platen of a typewriting machine and has for its primary object to facilitate the filling in of continuous-strip invoice forms wherein a number of individual and identically similar invoice-forms are provided on a web or continuous strip of paper, successive forms being separated by rows of perforations, for tearing off said invoice after being written upon.

According to the present invention means are provided whereby, after an invoice blank has been filled, the platen may be rotated in the forward direction (*i. e.*, so as to advance the web) through an automatically determined distance, to bring the first blank of the next invoice to the printing point, that is, to the proper position for commencing writing thereon, *i. e.* at a point immediately below the heading printed on the new invoice.

I employ a device to limit the extent to which the platen may be rotated line-by-line. This device is in the nature of an arm or member which is connected to the platen to rotate therewith, but which is capable of only limited rotation, whereby the rotation of the platen is limited. As the operator typewrites the invoice, the platen is rotated line-by-line together with said arm; and at the conclusion of the writing of the invoice, the platen is rotated further by the operator, until said arm is arrested by a stop. The platen is now in a position to begin the writing of the first line on a new invoice. Said arm is now set backwardly, while the platen remains stationary; a stop being provided to limit the return motion or setting of said arm. At the conclusion of said return motion, the arm reconnects to the platen, and is therefore ready to arrest the latter again in proper position to begin the first line of writing on the succeeding invoice.

In the accompanying drawings, Figures 1

and 2 are similar end views of the device of the present invention in its preferred form, the pawl-carrying arm being shown in Fig. 1 as having been turned backward until arrested by the adjustable stop, and in Fig. 2 as having been turned forward until arrested by a stop, the hand-wheel on the end of the platen-spindle being removed in each case. Fig. 3 is a plan view of the parts in the position shown in Fig. 1. Fig. 4 is a horizontal section on line 4—4 of Fig. 1. Fig. 5 is a section of the pawl and immediately adjacent parts, taken on the axial plane of the locking bolt (line 5—5 of Fig. 2); this figure being drawn to a larger scale.

In the form of the invention illustrated in the drawings, a ratchet-wheel A having a number of teeth equal to that of the usual line-space ratchet wheel M, and corresponding to the number of line-spaces comprised in one revolution of the platen B, or spaced in agreement with the line-space distances on the platen, is mounted fast on the platen-spindle *b* and is engaged by a spring-pressed pawl or dog C pivoted by a screw J on a radius-arm D forming a driver for the platen and rigidly connected to a hand-wheel *d* (or equivalent driving device), said arm D being mounted to rotate concentrically with the platen but independently thereof. Said pawl C forms a clutch and the forward revolution of the platen B (and therefore of the ratchet wheel A) produced by means of the ordinary line spacing mechanism, will cause arm D and pawl C to turn with the platen, because the pawl and arm will be driven by the ratchet A, which rotates with the platen. The platen may be rotated forwardly by the hand-wheel *d* (but not backwardly) through the pawl C, a spring *j* holding the pawl locked to the ratchet wheel A during such forward movement, but permitting the pawl to ride over the ratchet teeth during the backward rotation of the hand-wheel *d*.

The forward rotation of the platen B for each invoice is limited by a stop E, adapted to be encountered by the pawl C. The extent of the re-setting or free backward rotation of the pawl C about the platen axis is determined by an adjustable stop *f*, which is placed at such a distance from the stop E as to correspond to the length of one invoice or printed section of the web.

The continuous invoice-strip or web is introduced into the machine, in proper position to receive the first line of writing on the first invoice-form or section. The first 5 invoice or blank is then written and spaced line-by-line in the usual manner. After the completion of the invoice, the platen is advanced or rotated by means of the hand-wheel *d* as far as it will turn; the spring *j* being strong enough to carry around the arm *D* with the wheel *A*. This final forward revolution of the platen *B* will be automatically arrested by the engagement of the pawl *C* with the stop *E* when the position is reached for commencing writing upon the next invoice form or section; whereupon the pawl *C* must be re-set or shifted back until arrested by the stop *f*.

The stop *f* is constantly in use to determine the position to which the platen shall be rotated to bring a fresh blank upon a printed roll or strip of paper to writing position. For this purpose, the stop *f* is adjustably mounted in a stationary disk *G*, 20 whereby the angular distance between said stop and the stop *E* may be adjusted to correspond with the length of the blanks. The distance between the stop *f* and the stop *E* being constant, the hand-wheel *d* when operated will always bring the platen into position for beginning the next blank regardless of how much line-spacing has been done on the preceding blank.

The adjustable stop *f* may be of any well-known construction such as a spring-pressed bolt carried by a socket on an arm *F*¹ rotatable about the platen-axis, the bolt *F* being adapted to engage any one of a circular series of holes *g* provided in the 35 stationary disk *G* mounted concentrically with the platen axis and serving also to carry the stop *E*, while the head *f*¹ of the bolt serves for withdrawing the latter from the holes *g* and for turning the arm *F*¹ about the disk *G* as required.

As it may be necessary, particularly when first adjusting the invoice-strip in position relatively to the printing-point to rotate the platen *B* by usual means (such as the ordinary hand-wheel *d*¹ which is situated at the opposite end of the platen-spindle *b* from the device forming the subject of the present invention), through an angle greater than that which is bounded by the 50 fixed and adjustable stops *E* and *f* respectively, the pawl *C* is preferably provided with means whereby it may be temporarily thrown out of gear with the ratchet wheel *A* when required; and said means may be brought into permanent operation when the 55 machine is used for ordinary correspondence.

The drawings show a convenient device for this purpose, consisting of a spring-pressed locking-bolt *H* carried by the pawl

C and extending radially of the pin *J* by means of which the pawl *C* is pivotally attached to the arm *D* already mentioned; the bolt *H* being adapted to enter a recess *h* provided on the arm *D* so as to lock the pawl when the latter is thrown out of engagement with the teeth of the ratchet wheel *A* in opposition to the spring *j*. The stem of the bolt *H* may carry at its outer end a handle *K* whereby to withdraw the bolt from the recess *h* and turn the pawl *C* about the pin *J* as required.

The line-spacing devices in this class of machines usually comprise a line-space wheel *M*, connected to platen *B*, a pawl *N* to drive the wheel and platen, and a detent *O* to engage the wheel to hold it stationary. Wheels *A* and *M* should of course have equal numbers of teeth.

Having thus described my invention, I claim:

1. In a typewriting machine having a rotary platen and provided with line-spacing mechanism comprising a ratchet-wheel, the combination of a second ratchet-wheel turning as one with the platen and having teeth spaced in agreement with the tooth distances on said first-named ratchet-wheel, a manually rotatable radius-arm mounted concentrically with said second ratchet-wheel, a spring-pressed pawl pivoted to said arm and adapted to transmit motion from said second ratchet-wheel to the arm, a stop for arresting the forward movement of the radius-arm, a stationary disk mounted concentrically with said second ratchet-wheel and provided with a circular row of holes corresponding in number to the teeth of said second wheel, and a stop-arm freely rotatable about the axis of the disk and carrying a spring-pressed bolt adapted to engage any one of the holes in the disk; said stop-arm constructed to arrest the first-mentioned arm.

2. In a typewriting machine having a rotary platen and provided with line-spacing mechanism comprising a toothed line-space wheel, the combination of a ratchet-wheel turning as one with the platen and having teeth spaced in agreement with the tooth distances on said line-space wheel, a manually rotatable radius-arm mounted concentrically with the said ratchet-wheel, a pawl pivoted to said arm and spring-pressed into engagement with the said ratchet-wheel to transmit motion from the said ratchet-wheel to the arm, a stop for arresting the forward movement of the radius-arm, means for limiting the backward movement of said arm, and a spring-pressed bolt carried by the pawl and adapted to engage a notch on the radius-arm and hold the pawl off the said ratchet wheel while the radius-arm is rotated.

3. In a typewriting machine, the combi-

- 5 nation with a platen and line-spacing mechanism, of an arm, a yielding pawl to constantly connect the arm with the platen to be turned thereby, and to permit retraction of the arm independently of the platen, and relatively adjustable stops between which the arm may vibrate; one of said stops co-operating with the arm and pawl to lock the platen against advance rotation.
- 10 4. In a typewriting machine, the combination with a platen and line-space mechanism therefor, of a ratchet connected with the platen, an arm, a pawl on the arm normally in mesh with the ratchet, and stops between which the arm swings, one of said stops being adjustable, said line-space mechanism effective to turn the arm idly until its pawl strikes one of the stops to arrest the platen.
- 15 5. In a typewriting machine, the combination with a platen and line-space mechanism therefor, of a ratchet connected with the platen, an arm, a pawl on the arm normally in mesh with the ratchet, stops between which the arm swings, one of said stops being adjustable, said line-space mechanism effective to turn the arm idly until its pawl strikes one of the stops to arrest the platen, and a catch to hold the pawl in inoperative position.
- 20 6. In a typewriting machine, the combination with a platen and its axle, of a line-spacing mechanism, a ratchet fast on the axle, a swinging arm, a pawl yieldingly in mesh with the ratchet to advance the arm, and riding idly over the ratchet when the arm is manually swung in the opposite direction, and relatively adjustable stops between which the arm swings.
- 25 7. In a typewriting machine, the combination with a platen and a line-spacing mechanism therefor, of a pawl, means to connect said pawl to the platen to enable the pawl to be advanced thereby at the line-spacing operation, means independent of said line-spacing mechanism for moving said pawl to advance said platen, a stop to limit the advance of the pawl and platen, said pawl being retractile independently of the platen, and a stop to limit the retraction of the pawl; said pawl, after it has been retracted, being again movable into connection with the platen to be advanced therewith step-by-step in line-space direction, until arrested by the first-mentioned stop.
- 30 8. In a typewriting machine, the combination with a platen and a line-spacing mechanism therefor, of a pawl, means to connect said pawl to the platen to enable the pawl to be advanced thereby at the line-spacing operation, a stop to limit the advance of the pawl and platen, said pawl being retractile independently of the platen, and a stop to limit the retraction of the pawl, said stops being relatively adjustable.
- 35 9. In a typewriting machine, the combination with a platen and a line-spacing mechanism therefor, of a pawl, means to connect said pawl to the platen to enable the pawl to be advanced thereby at the line-spacing operation, a stop to limit the advance of the pawl and platen, said pawl being retractile independently of the platen, a stop to limit the retraction of the pawl, said stops being relatively adjustable, and means to silence said pawl at will, to permit indefinite advance rotation of the platen. 70
- 40 10. In a typewriting machine, the combination with a revolute platen and a line-spacing mechanism therefor, of a revolute arm, a pawl upon said arm, a wheel connected to said platen and engageable by said pawl to advance the pawl and arm at the line-spacing operation, a finger-piece connected to said arm to rotate the same and said pawl to advance said platen, a stop to limit the advance of the platen, pawl, arm and finger-piece, said pawl being retractile by said finger-piece independently of the platen and wheel, and a stop to limit the retraction of the pawl. 80
- 45 11. In a typewriting machine, the combination with a revolute platen and a line-spacing mechanism therefor, of a revolute arm, a pawl upon said arm, a wheel connected to said platen and engageable by said pawl to advance the pawl and arm at the line-spacing operation, a finger-piece connected to said arm to rotate the same and said pawl to advance said platen, a stop to limit the advance of the platen, pawl, arm and finger-piece, said pawl being retractile by said finger-piece independently of the platen and wheel, and a stop to limit the retraction of the pawl. 85
- 50 12. In a typewriting machine, the combination with a platen, of a platen-rotating mechanism comprising a ratchet rigidly connected to the platen, a driver, a handle thereon, said driver turning about the platen axis and relatively to the platen, and having a pawl to ride idly over the ratchet when the driver is moved rearwardly, and to rotate the ratchet and platen when the driver is moved forwardly, means to hold the pawl on the ratchet and cause the driver to be carried with the platen when the platen is rotated forwardly independently of power 110 supplied through the driver, a fixed stop in the path of the driver to arrest the driver when turned in one direction, and a stop adjustable relatively to the fixed stop and engaged by the driver to control the extent 115 of rotation of the platen. 120
- 55 13. In a typewriting machine, the combination with a platen, of platen-rotating mechanism including a driver mounted to rotate about the platen axis and a handle on 130

the driver, means coöperating with the driver to turn the platen throughout a variable number of line-spaces, said driver connected with the platen to turn the latter only when swung in one direction, and carried with the platen in said direction when the platen is rotated by power supplied independently of the driver, and stops in the path of the driver between which the driver plays, to regulate the amount of rotation of the platen, one of said stops being adjustable.

14. The combination with a rotary platen, of means to rotate the platen a predetermined distance, said means comprising a driver having a limited movement, the platen being rotatable a variable portion of said distance independently of power supplied through the driver, and after the driver has been brought to its starting position, and means to connect the driver to the platen and cause the platen, when the driver is operated to the limit of its forward movement, to be rotated by the driver the remainder only of said predetermined distance.

15. The combination with a rotary platen, of means to complete the rotation of the platen through a predetermined distance from its starting position, comprising a driver for said platen; means to determine the starting position of the driver; means to limit the stroke of the driver; the platen, after the driver has been brought to said starting position, being rotatable independently of power supplied through the driver, to introduce a work-sheet and feed it over the platen; and means to form a driving connection between the platen and driver and enable the driver, when operated to its forward limit after said independent rotation of the platen, to rotate the platen

through the remainder of such predetermined distance.

16. The combination with a rotary platen, of mechanism for effecting rotations of the platen through a predetermined distance, said mechanism comprising a driver, and initial and final stops for the driver, the platen being rotatable through a variable portion of said distance independently of power transmitted through the driver, means to move the driver during said rotation of the platen to a position corresponding to the extent of said rotation, said driver operable when moved from said position to its final stop, to complete the rotation of the platen through said predetermined distance from its starting position.

17. The combination with a rotary platen, of a driver rotatable about the platen axis, initial and final stops for the driver, means to connect the driver to the platen to cause the driver to rotate the platen, said driver operable when moved from its initial to its final position, to rotate the platen through a definite angle, and means for rotating the platen independently of power supplied through said driver for introducing and writing upon a work-sheet after the driver has been brought to its starting position, said connecting means operable to cause the driver to be moved during said last-named rotation of the platen to a position determined by the extent of said rotation, said driver operable when moved to its final stop position to complete the rotation of the platen through said angle.

JOHN JOSEPH COOPER.
